United States Patent Office

Des. 218,856
Patented Sept. 29, 1970

218,856

AIRCRAFT

Walter E. Fellers, Los Angeles, Calif., assignor to
Northrop Corporation, Beverly Hills, Calif., a corpo-
ration of California

Filed June 30, 1969, Ser. No. 17,938

Term of patent 14 years

Int. Cl. D12—07

U.S. Cl. D71—1

The invention herein described was made in the course of Contract No. F33657-67-C-1500 with the United States Air Force.

FIG. 1 is a perspective view viewed from above of the aircraft employing my design;

FIG. 2 is a top plan view thereof;

FIG. 3 is a side elevational view thereof, the opposite side thereof being identical; and

FIG. 4 is a front elevational view thereof.

I claim:

The ornamental design of an aircraft, substantially as shown and described.
